(57) **CLAIM**

The ornamental design for a window component extrusion 9552 and 9553, as shown and described.

DESCRIPTION

FIG. 1 is a top left isometric perspective view of the window component extrusion which is broken in the center indicating indefinite length.

FIG. 2 is a bottom right isometric perspective view of the window component extrusion shown in FIG. 1.

FIG. 3 is a top left isometric perspective view of a second embodiment of the window component extrusion which is broken in the center indicating indefinite length; and,

FIG. 4 is a bottom right isometric perspective view of the window component extrusion shown in FIG. 3.
